U.S. PATENT DOCUMENTS

D. 2,369 7/1866 Fracker D26/88
D. 85,668 12/1931 Schurmann D26/56

CLAIM

The ornamental design for a combined electric lamp
and mirror, as shown and described.

DESCRIPTION

FIG. 1 is a front perspective view of a combined elec-
tric lamp and mirror showing my new design;
FIG. 2 is a rear perspective view, the electric lamp
being omitted for convenience of illustration; and
FIG. 3 is a side elevational view thereof on an enlarged
scale, the mounting bolt being fragmentarily shown for
convenience of illustration.
